29 his ATTORNEY.

UNITED STATES PATENT OFFICE.

WILLIAM W. HIRK, OF ZION CITY, ILLINOIS. ASSIGNOR OF ONE-HALF TO RICHARD FEUERMAN.

SEWING-MACHINE ATTACHMENT.

1,392,872.

Specification of Letters Patent.

Patented Oct. 4, 1921.

Application filed February 2, 1917. Serial No. 146,229.

To all whom it may concern:

Be it known that I, WILLIAM W. HIRK, a citizen of the United States, and a resident of Zion City, county of Lake, and State of Illinois, have invented certain new and useful Improvements in Sewing-Machine Attachments, of which the following is a specification.

My invention relates to improvements in attachments for sewing machines, and has for its object the provision of an attachment arranged to be attached to an ordinary Singer hemstitch sewing machine of Class 72-W type and adapted to properly trim the edges 15 of the work and feed a cord thereto to be stitched along said edges.

The invention consists in the combinations and arrangements of parts hereinafter described and claimed.

20 The invention will be best understood by reference to the accompanying drawings forming a part of this specification, and in which,

Figure 1 is a sectional view of the attachment shown in position of use, the sewing machine head being indicated in dotted lines,

Fig. 2, a plan view illustrating the operative connection for operating the device,

30 Fig. 3, a plan view of the sewing plate as modified for use with the device,

Fig. 4, a sectional plan view of the device, and

Fig. 5, a detail view of a portion of a 35 piece of work sewed on the machine, when equipped with the attachment.

The preferred form of construction, as 40 illustrated in the drawings, comprises a supporting block 6 arranged to be secured to the ordinary sewing machine table or top plate 7, as shown. The block 6 carries a shear knife 8 set in the central slot 9 formed in the ordinary sewing plate 10 of the machine, the cutting edge 11 of the knife 8 being set flush with or just below the upper 45 surface of said plate along which the work being sewed passes. Another co-operating shear knife 12 carries an oscillatory arm 13 having an adjustable slot and pin connection

50 14 with the lower end of an adjustable link 15 connected, at its upper end, with an oscillatory arm 16 adjustably secured to the usual oscillatory shaft 17 of the sewing machine. The block 6 is provided with a beveled nose 55 18 arranged in the cutting path of the shear

knife 8 and adapted to separate the work cut thereby thus greatly facilitating the operation of said knife.

The block 6 also carries a laterally and forwardly extending arm 19 having a 60 branch arm 20 at its forward end provided with an upstanding perforated lug 21 adapted to serve as a cord guide. Another branch arm 22 is provided on arm 19 and carries a guide plate 23 arranged to co-operate with 65 guide lug 21 to direct a cord 23' into the machine with the work, said cord being stitched to the edge of the work by the ordinary stitches of the sewing machine, as will be readily understood.

70 The attachment is illustrated as used in conjunction with an ordinary Singer hemstitch sewing machine, the head 24 of which is indicated in dotted lines in Fig. 1. This head is provided with the usual sewing needle 25 and piercers 26 and 27 operating on the edge of the work 28 to form a hemstitch 29 therein, and the shear knives 8 and 12 cut or trim the edge of the cloth to produce a "picot" edge or an ornamental 80 scalloped effect, as indicated in Fig. 5, the cord 23' being bound into said edge, as indicated.

85 The arrangement set forth is simple and efficient in operation, will accurately and automatically trim the edge of the work, as indicated, and will permit of the turning of very sharp corners.

While I have illustrated and described the preferred form of construction for carrying 90 my invention into effect, this is capable of variation and modification without departing from the spirit of the invention. I, therefore, do not wish to be limited to the precise details of construction set forth, but 95 desire to avail myself of such variations and modifications as come within the scope of the appended claims.

Having described my invention what I claim as new and desire to secure by Letters 100 Patent is:

1. The combination with a sewing machine having the usual sewing table and vertical reciprocating needle, of a knife set with its cutting edge to the rear of said needle; 105 and a separating block having a beveled nose and set on said table to the rear and in the cutting path of said knife, substantially as described.

2. The combination with a sewing ma- 110

chine having the usual sewing table and vertically reciprocating needle, of a stationary knife blade set with its cutting edge to the rear of said needle and flush with the upper surface of said table; a coöperating movable knife blade above said table; means for operating said movable knife; and a separating block having a beveled nose and set on said table to the rear of said stationary blade in

the cutting path of said knife, substantially 10 as described.

In testimony whereof I have signed my name to this specification in the presence of two subscribing witnesses.

WILLIAM W. HIRK.
